UNITED STATES PATENT OFFICE.

CHARLES W. GRAHAM, OF ROME, NEW YORK, ASSIGNEE, BY MESNE ASSIGNMENTS, TO
AMERICAN CAN COMPANY, OF NEW YORK, N. Y., A CORPORATION OF NEW JERSEY.

ART OF MAKING CAN-BODIES.

970,622.

Specification of Letters Patent. Patented Sept. 20, 1910.

Application filed March 23, 1908. Serial No. 422,660.

To all whom it may concern:

Be it known that I, CHARLES W. GRAHAM, a citizen of the United States, residing at Rome, in the county of Oneida and State 5 of New York, have invented certain new and useful Improvements in the Art of Making Can-Bodies, of which the following is a full, clear, and exact description, such as will enable others skilled in the art to which it 10 appertains to carry on the same.

This invention relates to the art of making can bodies.

One of the objects thereof is to provide a simple and practical art for making strong, 15 durable and efficient can bodies.

Another object is to provide an art of the above type which can be quickly carried on without the aid of expensive and complicated apparatus.

20 Other objects will be in part obvious and in part pointed out hereinafter.

The invention accordingly consists in the several steps and the relation or order of each of the same with respect to one or more 25 of the others thereof as will be pointed out in the following description and the application of which will be indicated in the appended claims.

In the accompanying drawing, in which 30 certain features of this invention are diagrammatically illustrated, Figure 1 is a plan of a blank. Fig. 2 is a similar view of the same, with portions cut away. Fig. 3 is a similar view showing the member in a 35 edged or flanged condition. Fig. 4 is an end view showing the flanges interlocked one with another. Fig. 5 is a similar view showing the joint bumped or driven into closer condition. Fig. 6 is a similar view 40 showing the member forced into elliptical form, and solder applied to the joint. Fig. 7 is a similar view showing the device in a similar form and the joint wiped. Fig. 8 is a similar view, indicating a method of 45 cooling the solder. Fig. 9 is an end view of the member in round form and in finished condition.

Similar reference characters refer to similar parts throughout the several views of 50 the drawing.

Referring now to Fig. 2 of these drawings, there are shown at 1 notches or recesses

cut in the blank 2 shown in Fig. 1, which are preferably so positioned as to remove the corners of the original member. At the opposite edge of the blank 2 there are cut incisions preferably of V-shape, and positioned as indicated at 3. After these portions are cut away the edge portion 4 and the edge portion 5 comprehended between 55 incisions 3 are bent or flanged in opposite directions, leaving unflanged the corner portions 6. The member is then placed in the form shown in Fig. 4 of the drawings with the portions 4 and 5 interlocked or hooked 60 together and the portions 6 resting over and outside the portions 7 of the opposite end. The joint thus formed is then bumped, hammered, or otherwise driven into the tighter condition indicated at 8 in Fig. 5 of the 65 drawings. It may here be noted that by the expression "bumping" is meant any act whereby the parts to which it refers are forced into a more flat or more tightly interlocked condition. The member is then pref- 70 erably formed temporarily into the elliptical or otherwise distorted form shown in Fig. 6 of the drawing, and the solder 9 applied thereto along the entire seam or joint as shown. It may here be noted that the term 75 "elliptical" is used in a broad sense as covering any form in which the parts in which the seam lies are brought more nearly into a plane than when the member is in its free or normal condition. It is to be understood 80 that the seam lies are brought more nearly into the elliptical or otherwise distorted form," or similar terms, I mean so acting upon the body, against the resiliency thereof, but without destroying that quality, that a distorted shape will be given thereto tempor- 85 arily while the distorting means are operative, and that the body, by the assertion of its natural resiliency, will return to its original form when the operation of the distort- 90 ing means is discontinued. The joint is then wiped to remove the excess of solder as indicated at 10 in Fig. 7, the can preferably being maintained in elliptical condition, al- 95 though this invention in its broader aspects 100 is not limited to such distortion of the member acted upon. The solder is then cooled or hardened, as indicated in Fig. 8, preferably by the application of a jet of cold air,

as shown at 11. The member or can body is then in finished condition, insofar as this art is concerned, and may be permitted to resume its normal form, as indicated in 5 Fig. 9.

It will thus be seen that there is provided a simple and efficient art by which a strong, tight can body may be quickly formed. The interlocking of the flanges 10 holds the edges together to permit the can to be readily stretched into elliptical form, and this stretching or distorting action is peculiarly adapted to press the free ends 6 of the can against the portions on which they 15 lie, and thus not only economize solder but provide a thin end to the joint which admits of the can head being readily placed and sealed thereon. By the step of bumping or jamming together the form of seam 20 used, the lap joint portions or ends of the seam, are moreover, forced inwardly, and thus rendered more susceptible to the effect of placing the body in elliptical form. The entire art may, if desired, be carried on by 25 hand, or, if it is preferred, certain portions thereof may be automatically effected by machinery.

As various changes could be made in the above described method of carrying on this 30 invention without departing from the scope thereof and as the same could be carried on by the use of various types of apparatus, I intend that all matter set forth in this description or shown in the accompanying 35 drawings shall be interpreted as illustrative and not in a limiting sense. It is also to be understood that the language used in the following claims is intended to cover all of the generic and specific features of the invention herein described and all statements of the scope of the invention which, as a matter of language, might be said to fall therebetween.

Having described my invention what I 45 claim as new, and desire to secure by Letters Patent, is:

1. The art which comprises flanging the opposite edges of a blank, interlocking said flanged edges and producing substantially 50 the desired final form of body, distorting said body within the limit of its elasticity and holding it in temporarily distorted form, with said interlocking edges in a portion of reduced convexity, soldering said interlocking edges, permitting the joint to cool with the body in said distorted form, and permitting the body to resume its form first mentioned.

2. The art which comprises flanging the 60 opposite edges of a blank, interlocking said flanged edges and producing substantially the desired final form of body, forcing said body within the limit of its elasticity into temporarily elliptical form and holding it 65 in said form with said interlocking edges in

a portion of reduced convexity, soldering said interlocking edges, permitting the joint to cool with the body in said elliptical form, and releasing the body.

3. The art which comprises forming 70 spaced incisions in a blank, flanging the edge comprehended between said incisions, flanging the opposite edge of the blank, interlocking said flanged edges and producing substantially the desired final form of body, 75 forcing the body into temporarily distorted form with said interlocking edges in a portion of reduced convexity, soldering said opposite edges in assembled relation throughout said interlocking and overlapping portions thereof, permitting the joint to cool with said body in said distorted form, and releasing the body.

4. The art which comprises forming substantially V-shaped incisions in one edge of 80 a blank, flanging the edge comprehended between said incisions, flanging the opposite edge of the blank, interlocking said flanged edges with the unflanged portion overlapping and resting upon the outside of the corresponding portion of the opposite edge and producing substantially the desired final form of body, forcing the body into temporarily distorted form with said interlocking edges in a portion of reduced convexity, 85 soldering said opposite edges in assembled relation throughout the interlocking and overlapping portions thereof, permitting the joint to cool with said body in said distorted form, and then releasing the latter.

5. The art which comprises cutting away the corner portions of a blank, forming spaced incisions in the opposite edge of said blank, flanging the edge portions between said incisions and between said first portions, interlocking said flanged edges with the unflanged portions overlapping and resting upon the corresponding portions of the opposite edge and producing substantially the desired final form of body, forcing 100 the body into temporarily distorted form with said interlocking members in a portion of reduced convexity, soldering the opposite edges in assembled relation throughout said interlocking and overlapping portions 105 thereof, permitting the joint to cool with said body in said distorted form, and releasing the latter.

6. The art which comprises cutting away the corner portions at one edge of a blank, 110 forming substantially V-shaped incisions in the opposite edge of said blank, flanging the portions between said incisions and between said first portions, interlocking said flanged edges with unflanged portions overlapping and resting upon the corresponding portions of the opposite edge and producing substantially the final form of body, forcing the body into temporarily distorted form with said interlocking members in a portion 115

of reduced convexity, soldering the opposite edges in assembled relation throughout said interlocking and overlapping portions thereof, permitting the joint to cool with said body in said distorted form, and releasing the latter.

7. The art which comprises cutting away portions of one edge of a blank, flanging the edge comprehended between said portions, flanging the opposite edge of said blank, interlocking said flanged edges and producing substantially the desired final form of body, forcing the body into temporarily distorted form with said interlocking members in a portion of reduced convexity, soldering the opposite edges in assembled relation with the body in said distorted form, permitting the joint to cool with said body in said distorted form, and then releasing the latter.

20 8. The art which comprises cutting away portions of one edge of a blank, flanging the edge comprehended between said portions, forming incisions in the opposite edge spaced at a distance substantially equal to 25 the length of said flanged portion of said first edge, flanging the edge comprehended between said incisions, interlocking said flanged edges and producing substantially the desired final form of body, forcing the 30 body into temporarily distorted form with said interlocking edges in a portion of reduced convexity, soldering the opposite edges in assembled condition, permitting the joint to cool with said body in said distorted form, and releasing the latter.

9. The art which comprises cutting rectangular portions from one edge of a blank, flanging the edge portion comprehended therebetween, forming substantially V-shaped incisions in the opposite edge of 40 said blank, said incisions being spaced at a distance substantially equal to the length of said flanged edges, flanging the edge between said incisions, interlocking said flanged edges with the unflanged portions of the second edge overlapping and resting upon the outside of the corresponding portions of the opposite edge and producing substantially the desired final form of body, forcing said body into temporarily distorted form with said interlocking edges in a portion of reduced convexity, soldering the opposite edges in assembled relation throughout the overlapping and interlocking portions thereof, permitting the joint to cool with said body in said distorted form, and releasing the latter.

10. The art which comprises forming spaced incisions in a member, flanging the edge comprehended between said incisions, flanging the opposite edge of the member, interlocking said flanged edges with the unflanged portion overlapping and resting upon the outside of the corresponding portion of the opposite edge, holding said mem-

ber in elliptical form with said interlocked edges in a portion of reduced convexity, soldering said opposite edges in assembled relation throughout said interlocking and overlapping portions thereof, permitting 70 the joint to cool with the member in said elliptical form, and releasing the same.

11. The art which comprises forming substantially V-shaped incisions in one edge of a member, flanging the edge comprehended between said incisions, flanging the opposite edge of the member, interlocking said flanged edges with the unflanged portion overlapping and resting upon the outside of the corresponding portion of the opposite edge, holding 75 said member in elliptical form with said interlocked edges in a portion of reduced convexity, soldering said opposite edges in assembled relation throughout the interlocking and overlapping portions thereof, permitting 80 the joint to cool with said member in said elliptical form, and releasing the same.

12. The art which comprises cutting away the corner portions at one end of a member, 90 forming spaced incisions in the opposite edge of said member, flanging the edge portions between said incisions and between said first portions, interlocking said flanged edges with the unflanged portions overlapping and resting upon the outside of the corresponding portions of the opposite edge, holding 95 said member in elliptical form with said interlocking edges in a portion of reduced convexity, soldering the opposite 100 edges in assembled relation throughout said interlocking and overlapping portions thereof, permitting the joint to cool with said member in said elliptical form, and releasing the same.

13. The art which comprises cutting away the corner portions at one end of a member, forming substantially V-shaped incisions in the opposite edge of said member, flanging the portions between said incisions and between said first portions, interlocking said flanged edges with the unflanged portions overlapping and resting upon the outside of the corresponding portions of the opposite edge, holding said member in elliptical 105 form with said interlocking edges in a portion of reduced convexity, soldering the opposite edges in assembled relation throughout said interlocking and overlapping portions thereof, permitting the joint to cool 110 with said member in said elliptical form, and releasing the same.

14. The art which comprises cutting away portions of one end of a member, flanging the edge comprehended between said portions, flanging the opposite edge of said member, interlocking said flanged edges, holding said member in elliptical form with said interlocked flanges in a portion of reduced convexity, soldering the opposite 125

130

- edges in assembled relation, permitting the joint to cool with said member in said elliptical form, and releasing said member.
15. The art which comprises cutting away portions of one edge of a member, flanging the edge comprehended between said portions, forming incisions in the opposite edge spaced at a distance substantially equal to the length of said flanged portion of said first edge, flanging the edge comprehended between said incisions, interlocking said flanged edges, holding said member in elliptical form with said interlocking flanges in a portion of reduced convexity, soldering the same in assembled condition, permitting the joint to cool with said member in said elliptical form, and releasing the same.
16. The art which comprises cutting rectangular portions from one edge of a member, forming substantially V-shaped incisions in the opposite edge of said member, said incisions being spaced at a distance substantially equal to that between said first portions, flanging the edges between said incisions and between said first portions, interlocking said flanged edges with the unflanged portions of the second edge overlapping and resting upon the outside of the corresponding portions of the opposite edge, holding said member in elliptical form with the joint formed by said interlocking flanges in a portion of reduced convexity, soldering

the opposite edges in assembled relation throughout the interlocking and overlapping portions thereof, permitting the joint to cool with said member in said elliptical form, and releasing the same.

17. The art which comprises cutting rectangular portions from one edge of a member, forming substantially V-shaped incisions in the opposite edge of said member, said incisions being spaced at a distance substantially equal to that between said first portions, flanging the edges between said incisions and between said first portions interlocking said flanged portions with the unflanged portions of the second edge overlapping and resting upon the outside of the corresponding portion of the opposite edge, bumping the joint formed by said interlocking flanges, holding said member in elliptical form with said joint in a portion of reduced convexity, soldering the opposite edges in assembled relation throughout the interlocking and overlapping portions thereof, permitting the joint to cool with said member in said elliptical form, and releasing said member.

In testimony whereof I affix my signature, in the presence of two witnesses.

CHARLES W. GRAHAM.
